United States Patent Office

Des. 208,833
Patented Oct. 3, 1967

208,833

WASTE RECEPTACLE

Edward Hess Prager, 5733 Greenspring Ave.,
Baltimore, Md. 21209

Filed Jan. 11, 1966, Ser. No. 616

Term of patent 14 years

(Cl. D58—17)

FIG. 1.

FIG. 2.

FIG. 3.

FIG. 1 is a side elevational view of a waste receptacle, showing my new design;

FIG. 2 is a top plan view; and

FIG. 3 is a sectional view thereof taken on the line 3—3 of FIG. 1.

I claim:

The ornamental design for a waste receptacle, as shown.
